US0D1044653S

(12) **United States Design Patent** (10) Patent No.: **US D1,044,653 S**
(45) Date of Patent: ** Oct. 1, 2024

(54) **REAR DIFFUSER FOR MOTOR VEHICLE**

(71) Applicant: **Dr. Ing. h.c. F. Porsche**
Aktiengesellschaft, Stuttgart (DE)

(72) Inventor: **WooSung Chung**, Stuttgart (DE)

(73) Assignee: **Dr. Ing. h.c. F. Porsche**
Aktiengesellschaft (DE)

(**) Term: **15 Years**

(21) Appl. No.: **29/815,684**

(22) Filed: **Nov. 16, 2021**

(30) **Foreign Application Priority Data**

May 18, 2021 (EM) 008544944-0005

(51) **LOC (14) Cl.** **12-16**

(52) **U.S. Cl.**
USPC **D12/163**

(58) **Field of Classification Search**

USPC D12/86, 90, 91, 92, 98, 163, 164, 169,
D12/190, 196
CPC B62B 9/16; B60K 11/08; B62D 25/08;
B60R 19/52
